US00D942718S

(12) **United States Design Patent** (10) Patent No.: **US D942,718 S**
(45) Date of Patent: **** Feb. 1, 2022**

(54) **BLOWER**

(71) Applicant: **GLOBE (JIANGSU) CO., LTD,**
Jiangsu (CN)

(72) Inventor: **Chang Wang**, Jiangsu (CN)

(73) Assignee: **GLOBE (JIANGSU) CO., LTD,**
Changzhou (CN)

(**) Term: **15 Years**

(21) Appl. No.: **29/704,770**

(22) Filed: **Sep. 6, 2019**

(30) **Foreign Application Priority Data**

Mar. 8, 2019 (CN) 201930094309.5

(51) LOC (13) Cl. **15-05**

(52) U.S. Cl.
USPC **D32/15**

CLAIM

The ornamental design for a blower, as shown and described.

DESCRIPTION

FIG. 1 is a top, front and right side perspective view of a blower showing my new design;

FIG. 2 is a top, front and left side perspective view thereof;

FIG. 3 is a bottom, rear and right side perspective view thereof;

FIG. 4 is a bottom, rear and left side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof; and,

FIG. 10 is a bottom plan view thereof.

The broken lines in the drawings illustrate portions of the blower which form no part of the claimed design.

1 Claim, 10 Drawing Sheets
